SADDLE CLAMP

Telford L. Smith, South San Francisco, Calif.

Application December 10, 1948, Serial No. 150,091

Term of patent 14 years

(CL. D54—2)

To all whom it may concern:

Be it known that I, Telford L. Smith, a citizen of the United States of America, residing at 567 Magnolia Avenue, South San Francisco, in the county of San Mateo and State of California, have invented a new, original, and ornamental Design for a Saddle Clamp, of which the following is a specification, reference being had to the accompanying drawings, forming part thereof.

In the drawings:

Fig. 1 is a view in perspective of a saddle clamp, showing my new design;

Fig. 2 is a top plan view of the same;

Fig. 3 is a front view in elevation of the same;

Fig. 4 is a side view in elevation of the same; and

Fig. 5 is a bottom plan view of the same.

I claim:

The ornamental design for a saddle clamp, substantially as shown.

TELFORD L. SMITH.
